UNITED STATES PATENT OFFICE.

MATTHIAS BROCK, OF BOSTON, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

LASTING-MACHINE.

1,284,870.

Specification of Letters Patent. Patented Nov. 12, 1918.

Application filed June 1, 1915. Serial No. 31,490.

To all whom it may concern:

Be it known that I, MATTHIAS BROCK, a citizen of the United States, residing at Boston, in the county of Suffolk and State of Massachusetts, have invented certain Improvements in Lasting-Machines, of which the following description, in connection with the accompanying drawings, is a specification, like reference characters on the drawings indicating like parts in the several figures.

This invention relates to lasting machines of the bed type, an example of which is shown in prior Letters Patent of the United States, No. 1,018,477, granted on my application Feb. 27, 1912.

One feature of the invention consists in improved wiper operating mechanism. In the lasting machine to which the present invention is shown as applied for the purpose of illustration the last is carried on a support and toe embracing wipers are movable upwardly relatively to the last in wiping contact with the upper that covers the side faces of the last for the purpose of conforming the upper smoothly to the contour of the last. When the wipers have reached the plane of the shoe bottom they are closed and advanced to lay the marginal portion of the upper into position to be fastened to the innersole. Many modern lasts differ in shape on the two side faces of the toe, the inner side being inclined inwardly toward the sole face and the outer side being reversely inclined. Consequently, if the wipers are closed around the toe at the usual distance of a quarter to a half inch below the sole and are then upraised to wipe upwardly, the receding inner side face of the last allows the wipers to lose effective wiping engagement with the upper on that side of the shoe. This leaves the upper loose and permits wrinkles to form, while the outward inclination of the opposite side of the last causes the wipers to pinch there and sometimes damage the upper as they rise. Another difficulty encountered in lasting shoes on such lasts is that when the wipers are closed over the innersole the right distance on the outer side of the toe they do not wipe the upper over far enough on the inner side of the toe. This has important disadvantages in operating upon McKay shoes and upon welt shoes. In making McKay shoes it results in locating the lasting tacks so close to the edge of

the innersole on the inner side of the toe that they are in the way of the awl and needle of the sole sewing machine. In making welt shoes the failure of the wipers to reach over the innersole the proper distance on the inner side of the toe leaves the upper in improper relation to the lip of the innersole, causing defective work in the weltling operation. This feature of the invention comprises the combination of lasting means with last holding means between which there is capacity for relative bodily movement transversely of the last. In the illustrated machine embodying this feature of the invention the shoe is jacked in fixed position and the end lasting means comprises toe embracing wipers and a toe embracing band which are mounted for bodily movement transversely of the machine and relatively to the last during the upward wiping operation of the lasting means.

Another feature of the invention consists in means for effecting automatically a relative bodily movement of end lasting means and the last transversely of the machine during an upward wiping operation. This is shown as embodied in guiding means for the lasting means arranged to cause the lasting means to rise in a path inclined to the vertical. Means is provided for effecting adjustment by which the path can be varied and its inclination reversed for right and left lasts.

A further feature of this invention consists in improved end band mechanism. Flexible end embracing bands located below the wipers are employed for supplementing the operation of the wipers in conforming the upper to the contour of the side faces of the last and holding the upper while the wipers are closed to lay the upper into lasted position and are then backed away to permit the upper to be fastened. This feature of the invention comprises improved band mechanism by which the band is caused to fit differently shaped lasts and to clamp the upper tightly to a last particularly along the rear portions of the sides of the toe. Heretofore fixed abutments have been employed relatively to which wedge bars have had a variable length of movement to draw the band against the end and close it against the sides of the toe. By the illustrated embodiment of this feature of the invention the abutments are made movable against a

yielding resistance so that the wedge bars can have an unrestricted length of movement to draw the upper against the end of the toe and so that said bars will apply substantially the same pressure to force the band inwardly against the sides of toes varying in width. Preferably also operating means is provided which imparts an inward movement to the abutments to accelerate the inward movement of the band which the wedge faces of the bars produce. Another feature of the present invention consists in improved means for closing the band from the wiper closing lever. This organization insures proper use of the band and provides for such use without loss of the operator's time.

A band lining support which is formed to produce pressure of the band against the edge of the shoe is a feature of the invention. At the edge of the shoe is the place where the upper shaping and holding functions of the band are most important and bands have been made with wedge shaped leather rands arranged to increase the thickness of the band at its top to obtain pressure at the edge of the shoe. Because of the thickness of the compressible material of the band made in this way the pressure applied to the edge of the shoe is not as firm as is desirable and, furthermore, such bands soon lose definiteness of shape. I have discovered that firmer pressure at the edge of the shoe and greater permanence of shape of the band can be obtained by forming the band support to present a rigid inwardly and upwardly inclined supporting face for the upper portion of the band lining.

Another feature of the invention consists in improved mechanism for compressing the marginal portions of the overwiped upper materials between the wipers and the last bottom more effectively than has heretofore been possible and with less effort by the operator, and in the embodiment of the invention shown the work may be locked under compression.

A further feature of the invention consists in improved means for positioning the upper at the tip seam. The forward strains applied to uppers in lasting toes under many conditions produce more or less tendency toward forward displacement or bowing of the middle portion of the tip seam. This feature of the invention provides means for pressing the middle portion of the tip seam backwardly. In the illustrated embodiment of this feature of the invention the toe rest is arranged to be forced backwardly under the shoe while the tip seam is clamped hard upon said rest.

Another feature of the invention consists in wiper operating means constructed and arranged to impart a different movement to end embracing wipers at one side of the last

from the movement given to the wipers at the other side of the last. The contour of the bottom face of the heel part of many lasts differs substantially from the contour of that of the part embraced by the heel band. This results, for example, from deeply inutting the shanks of the lasts as is characteristic of some styles of lasts. By the use of this invention the heel wipers may occupy retracted positions, symmetrical or otherwise relatively to the median line of the heel portion of the last, in which they offer no obstruction to presenting a shoe to the heel band, and may then be advanced and closed farther at one side of the shoe than at the other to reach in over a deeply cut away shank and lay the upper into properly lasted position at both sides of the last bottom. As shown a closing movement having predetermined differences at the two sides of the heel is obtained automatically by the construction and arrangement of the wiper operating means.

These and other features of this invention, including certain details of construction and more important combinations of parts, will now be explained in connection with the accompanying drawings, which show an illustrative embodiment of the invention, and will then be pointed out in the claims.

Referring now to the drawings,

Figure 1 is a side elevation of a lasting machine equipped with the present invention.

Fig. 2 is a plan view of the forepart of the machine on an enlarged scale.

Fig. 3 is an elevation looking from the middle portion of the machine forwardly.

Fig. 4 is a longitudinal vertical section through the toe band of the machine.

Fig. 5 is a transverse vertical section through a side portion of the toe band.

Fig. 6 is a plan view of the rear part of the machine on the same scale as Fig. 2 and showing mechanism for closing heel embracing wipers unsymmetrically for acting properly on a certain shape of last.

Fig. 7 is a transverse vertical section through the shank portion of a shoe and illustrating the unsymmetrical movement which the wipers may be given for the purpose of reaching into a deep shank.

Figs. 8-11 illustrate successive positions of the toe lasting mechanism.

The frame of the machine sustains toe lasting mechanism, shown at the left of Fig. 1 and in Fig. 2, and heel lasting mechanism, shown at the right of Fig. 1 and in Fig. 6, and between the toe and the heel lasting mechanisms are located the toe rest and the heel post. The toe lasting mechanism is vertically movable and its depending stem 6 is guided vertically in the table or head of the frame work and connected by a rod and belt

crank with a double-ended treadle 8, the weight of the toe lasting head being partially counterbalanced by springs 9. The head of the stem 6 supports a plate 10 which, with the superposed toe lasting mechanism, is adjustable longitudinally of the machine by a screw and hand wheel 11 for adaptation to shoes of different lengths, the operative position of the heel lasting mechanism 10 lengthwise of the machine being constant and the toe lasting mechanism alone being lengthwise adjustable. Above the plate 10 is a plate 13, Figs. 1 and 2, which is movable in a right line transversely of the machine 15 by means shown in Fig. 3, which will be later described. The plate 13 has an undercut groove, Fig. 1, in which slides a correspondingly formed rib depending from a plate 15, said groove and rib being curved about a center which is located substantially under the end of the toe of the last when a shoe is in the macaime. A screw-rod, Fig. 2, having a hand wheel 16 effects and maintains adjustment of plate 15 about a pivotal connection at said center. For convenience in removing the toe lasting mechanism from the machine the pivotal connection between the plate 15 and the underlying plate 13 is made by a flanged stud 17 depending from the plate 15 and adapted when the plate 15 is swung laterally to an extreme position to enter a socket in the underlying plate 13. The head of the stud is locked under a flange of the socket when the plate 15 is returned to a normal position. This connection between the stud 17 and its socket is in the nature of a bayonet joint. From the plate 15 rise projections to which are pivotally connected at 20 the tipping head 22 which is adjusted and maintained in adjusted position about said pivot 20 by a screw and hand crank 25 to adapt the toe lasting mechanism to the inclination of the forepart of the last bottom. The tipping head 22 is 45 formed in its upper face as a half sleeve upon which fits a cap plate 24 having a complementary formation to present a long bearing extending lengthwise of the shoe. In this bearing is mounted the cylindrical stem 50 of the toe wiper carrying plate 30. This stem has a lug projecting through the bearing and engaged by a forked block which is movable by a screw and hand crank 26 for adjusting the toe wiper carrying plate about an axis extending lengthwise of the machine to adapt the wipers to the transverse inclination of the forepart of the last bottom. Within a horizontal guideway formed in the plate 30 are located the cam plates 32 to 60 which the wipers 35, Fig. 2, are detachably connected, said plates being provided with the usual cam slots in which stand roller studs screwed to the plate 30 and causing the wipers to close when they are advanced. 65 The advancing movement of the wipers is effected through a plunger rod 37 operated by a hand lever 36. The double-ended treadle 8 provides means for lifting the toe head whereby the wipers, which will have been caused to embrace the toe portion of the last below the last bottom, may be caused to wipe up and mold the upper to the side faces of the toe portion of the last. After the wipers reach the plane of the shoe bottom they are further advanced and closed to lay the upper materials inwardly over the innersole upon the last bottom. The general organization of the machine thus far discussed is or may be substantially the same as is fully shown and described in said prior Patent No. 1,018,477, and need not be here further explained.

After the wipers have been advanced over the last bottom, precision of shape of the shoe at the toe calls for the application of heavy compression in order to put the upper materials into condition for presenting a suitably compact and smooth surface upon which to lay and attach the welt or the outsole. Upper compressing movement of the wipers may be produced by foot pressure upon the right-hand end of the treadle 8, but for the best results it is desirable to employ a substantially greater stock compressing force than it is practical to apply by means of such a treadle, and to meet these conditions the novel lever mechanism shown in Fig. 1 has been devised to supplement the treadle 8. This mechanism comprises a long hand lever 40 constituting one arm of a rock-shaft 42 which is separate from the treadle shaft and is journaled in a bracket rigidly secured to the frame of the machine. The rock-shaft has a relatively short arm pivotally connected at 44 to a link or swinging bar 45 the upper portion of which carries a normally free pawl which is adapted to be engaged with ratchet teeth 46 formed on the left hand edge of the stem 6 of the toe lasting head. The pawl is normally free from the ratchet so that the toe lasting head can be raised and lowered by the operator's foot on the treadle 8 without vibrating hand lever 40. When the wipers have been initially pressed down by the treadle upon the overwiped upper the pawl will be engaged with the ratchet by lever arm 40 of the rock-shaft 42 in the most advantageous position for the operator to use his strength.

Force then applied to the long upright lever arm is multiplied through the short arm of the rock-shaft and is communicated through the described connections to force the wipers downwardly and apply very heavy compression to the upper materials for ironing them down upon the last bottom. For maintaining the pawl on bar 45 normally disengaged from the ratchet 46, in order to permit unobstructed movement of 130

the stem 6 by the treadle 8, a spring 48 is arranged as shown in Fig. 1 and connections are provided by which the initial movement of arm 40 is caused to force the bar 45 into engagement with the ratchet. These connections include an arm 50 projecting from the rock-shaft toward the left in Fig. 1 and having a guideway in which a spring 52 upholds the stem of a cam 54 having a slot 51 by which it engages a stud extending from the bar 45. The cam slot is eccentric to the rock-shaft, its formation being such that initial movement of the rock-shaft transmits pressure through the cam to the 10 stud on the bar 45 to swing the pawl carried by the bar against the ratchet 46. During continued movement of lever arm 40 for compressing the upper stock the cam slides over the stud and its stem slides in 15 the arm 50. Movement of the arm 40 toward the left in Fig. 1 promptly disengages the bar 45 from the ratchet 46, and allows the treadle 8 at once to assume control of the toe lasting head for uplifting the wipers 20 to permit their withdrawal from the shoe bottom without dragging outwardly over the upper. A spring pin 55 provides a buffer to arrest outward movement of the arm 40 produced by spring 48 when said arm is 25 released. A ratchet bar 56 on the machine frame and a pawl 57 pivoted on the lever arm 40 provides means for locking the parts with the wipers compressing the overlasted upper upon the last bottom. An unlocking 30 bar 58 is pivoted to the frame with one end behind the pawl 57 and the other end in position to be engaged by the knee plate 59 of the unjacking mechanism of the machine. This combination provides for releasing 35 compression without attention from the operator before the unjacking mechanism begins to operate.

The machine is shown as provided with a toe embracing band 70 which constitutes an outer close-fitting form or mold at the edge of the shoe bottom while the wipers are operated to compress powerfully the upper on the margin of the shoe bottom whereby a sharply defined angular edge is produced at 45 the junction of the side and bottom faces of the shoe. Such a molded edge assists materially in preventing the upper from slackening back during the period between the lasting and the sewing of the shoe. The band 50 is mounted directly below the acting edge of the toe wipers 35, Figs. 2 and 3, and comprises a supporting chain 72 and a non-abrasive lining member. The chain is connected at its outer ends to transverse levers 55 74 which are fulcrumed on slide bars 75, Fig. 2, which are mounted within the wiper carrying plate 30 for movement lengthwise of the machine. The ends of the slide bars 75 remote from the band are pivotally connected to a cross-head 78 which is pivoted to 60 the stem 6 by the treadle 8, a spring 48 is arranged as shown in Fig. 1 and connections are provided by which the initial movement of arm 40 is caused to force the bar 45 into engagement with the ratchet. These connections include an arm 50 projecting from the rock-shaft toward the left in Fig. 1 and having a guideway in which a spring 52 upholds the stem of a cam 54 having a slot 51 by which it engages a stud extending from the bar 45. The cam slot is eccentric to the rock-shaft, its formation being such that initial movement of the rock-shaft transmits pressure through the cam to the 10 stud on the bar 45 to swing the pawl carried by the bar against the ratchet 46. During continued movement of lever arm 40 for compressing the upper stock the cam slides over the stud and its stem slides in 15 the arm 50. Movement of the arm 40 toward the left in Fig. 1 promptly disengages the bar 45 from the ratchet 46, and allows the treadle 8 at once to assume control of the toe lasting head for uplifting the wipers 20 to permit their withdrawal from the shoe bottom without dragging outwardly over the upper. A spring pin 55 provides a buffer to arrest outward movement of the arm 40 produced by spring 48 when said arm is 25 released. A ratchet bar 56 on the machine frame and a pawl 57 pivoted on the lever arm 40 provides means for locking the parts with the wipers compressing the overlasted upper upon the last bottom. An unlocking 30 bar 58 is pivoted to the frame with one end behind the pawl 57 and the other end in position to be engaged by the knee plate 59 of the unjacking mechanism of the machine. This combination provides for releasing 35 compression without attention from the operator before the unjacking mechanism begins to operate.

The machine is shown as provided with a toe embracing band 70 which constitutes an outer close-fitting form or mold at the edge of the shoe bottom while the wipers are operated to compress powerfully the upper on the margin of the shoe bottom whereby a sharply defined angular edge is produced at 45 the junction of the side and bottom faces of the shoe. Such a molded edge assists materially in preventing the upper from slackening back during the period between the lasting and the sewing of the shoe. The band 50 is mounted directly below the acting edge of the toe wipers 35, Figs. 2 and 3, and comprises a supporting chain 72 and a non-abrasive lining member. The chain is connected at its outer ends to transverse levers 55 74 which are fulcrumed on slide bars 75, Fig. 2, which are mounted within the wiper carrying plate 30 for movement lengthwise of the machine. The ends of the slide bars 75 remote from the band are pivotally connected to a cross-head 78 which is pivoted to 60 the stem 6 by the treadle 8, a spring 48 is arranged as shown in Fig. 1 and connections are provided by which the initial movement of arm 40 is caused to force the bar 45 into engagement with the ratchet. These connections include an arm 50 projecting from the rock-shaft toward the left in Fig. 1 and having a guideway in which a spring 52 upholds the stem of a cam 54 having a slot 51 by which it engages a stud extending from the bar 45. The cam slot is eccentric to the rock-shaft, its formation being such that initial movement of the rock-shaft transmits pressure through the cam to the 10 stud on the bar 45 to swing the pawl carried by the bar against the ratchet 46. During continued movement of lever arm 40 for compressing the upper stock the cam slides over the stud and its stem slides in 15 the arm 50. Movement of the arm 40 toward the left in Fig. 1 promptly disengages the bar 45 from the ratchet 46, and allows the treadle 8 at once to assume control of the toe lasting head for uplifting the wipers 20 to permit their withdrawal from the shoe bottom without dragging outwardly over the upper. A spring pin 55 provides a buffer to arrest outward movement of the arm 40 produced by spring 48 when said arm is 25 released. A ratchet bar 56 on the machine frame and a pawl 57 pivoted on the lever arm 40 provides means for locking the parts with the wipers compressing the overlasted upper upon the last bottom. An unlocking 30 bar 58 is pivoted to the frame with one end behind the pawl 57 and the other end in position to be engaged by the knee plate 59 of the unjacking mechanism of the machine. This combination provides for releasing 35 compression without attention from the operator before the unjacking mechanism begins to operate.

The machine is shown as provided with a toe embracing band 70 which constitutes an outer close-fitting form or mold at the edge of the shoe bottom while the wipers are operated to compress powerfully the upper on the margin of the shoe bottom whereby a sharply defined angular edge is produced at 45 the junction of the side and bottom faces of the shoe. Such a molded edge assists materially in preventing the upper from slackening back during the period between the lasting and the sewing of the shoe. The band 50 is mounted directly below the acting edge of the toe wipers 35, Figs. 2 and 3, and comprises a supporting chain 72 and a non-abrasive lining member. The chain is connected at its outer ends to transverse levers 55 74 which are fulcrumed on slide bars 75, Fig. 2, which are mounted within the wiper carrying plate 30 for movement lengthwise of the machine. The ends of the slide bars 75 remote from the band are pivotally connected to a cross-head 78 which is pivoted to 60 the stem 6 by the treadle 8, a spring 48 is arranged as shown in Fig. 1 and connections are provided by which the initial movement of arm 40 is caused to force the bar 45 into engagement with the ratchet. These connections include an arm 50 projecting from the rock-shaft toward the left in Fig. 1 and having a guideway in which a spring 52 upholds the stem of a cam 54 having a slot 51 by which it engages a stud extending from the bar 45. The cam slot is eccentric to the rock-shaft, its formation being such that initial movement of the rock-shaft transmits pressure through the cam to the 10 stud on the bar 45 to swing the pawl carried by the bar against the ratchet 46. During continued movement of lever arm 40 for compressing the upper stock the cam slides over the stud and its stem slides in 15 the arm 50. Movement of the arm 40 toward the left in Fig. 1 promptly disengages the bar 45 from the ratchet 46, and allows the treadle 8 at once to assume control of the toe lasting head for uplifting the wipers 20 to permit their withdrawal from the shoe bottom without dragging outwardly over the upper. A spring pin 55 provides a buffer to arrest outward movement of the arm 40 produced by spring 48 when said arm is 25 released. A ratchet bar 56 on the machine frame and a pawl 57 pivoted on the lever arm 40 provides means for locking the parts with the wipers compressing the overlasted upper upon the last bottom. An unlocking 30 bar 58 is pivoted to the frame with one end behind the pawl 57 and the other end in position to be engaged by the knee plate 59 of the unjacking mechanism of the machine. This combination provides for releasing 35 compression without attention from the operator before the unjacking mechanism begins to operate.

jaçent machine and to use each machine on the range of sizes for which it is particularly adjusted.

The slide bars 75 have cam faces or inclines 88, Fig. 2, on their outer edges which coöperate with stops 90 to wedge the end portions of the band inwardly for closing the band hard against the sides of the toe in response to forward movement of the 10 slide bars and concurrently with the rearward pulling movement on the band ends. The stops 90 are formed as cams on the inner arms of levers which are fulcrumed to fixed lateral extensions of the wiper carrying plate 30 and the outer ends of these cam levers are engaged by springs 92 through which pressure is applied from the previously mentioned cross-head 78 for holding the cams or wedge abutments to their work 20 and tending to turn the cams in the direction to supplement the action of the inclines 88 in forcing the end portions of the toe band inwardly. These springs also afford relief by allowing the cam levers to turn 25 backward, as in Fig. 11, while the inclines 88 complete their stroke. The springs 92 are guided on rods 94 which slide freely through pivot blocks carried on the outer ends of the stop levers 90 and the cross-head 78. The cam levers constitute means to produce edgewise movement of the slide bars 75 and the operating connections, including the springs 92, position the cam levers and thereby position the slide bars differently 35 for right and left lasts during the first part of the band closing movement, after which said connections can yield while the slide bars advance relatively to the cam levers to cause the inclines 88 on the bars so positioned 40 to apply approximately equal pressure to the opposite sides of the right or the left shoe end embraced by the band. The friction of the relatively moving parts is such that under the action of the springs 82 and 45 92 the slide bars 75 hold the band hard closed against the shoe while the lost motion between the slide 77 and lever 36 is utilized in backing off the wipers to uncover the tacking line on a McKay shoe toe or to permit 50 the toe wiring operation on a welt shoe toe. Specific friction means may be arranged for this purpose if needed.

The toe band is removably supported on a bracket 96 which is formed to present a shelf 55 upon which the middle portion of the lower edge of the band rests as shown in Fig. 4. The band is confined in place by the engagement with the bracket 96 of a horizontal stud 98, projecting from a plate 97 secured 60 to the band, and by the engagement of a vertical spring pin 99 with a lower arm of the plate 97. The band chain 72 is fastened in the middle to the bracket 96 and carries on its ends depending plates 102 having 65 forwardly opening slots. These slots receive

headed studs 100 located on the outer sides of the band for supporting the end portions of the band. This supporting means permits free longitudinal withdrawal of the band after the pin 99 has been pulled down. 70

The bracket 96 and therefore the toe band is preferably supported for adjustment lengthwise of the machine and relatively to the wipers by a rod 104 connected to the bracket as shown in Fig. 4 and extending 75 longitudinally to the left hand end of the machine, Fig. 1, where it is provided with a hand wheel 106. The rod has a screw-threaded connection with a collar, Fig. 4, which has a limited amount of endwise play 80 in the lower portion of the toe wiper carrying plate 30. By means of this threaded connection the toe band can be advanced or retracted relatively to the wipers. The rod 104 is encircled by a spring which is maintained under compression, as shown in Fig. 4, between said collar and the plate 30 and therefore permits the rod 104 and its collar, the bracket 96, and the toe band to have a limited amount of forward and backward 85 movement with relation to plate 30. This play allows the toe band to move forwardly against the end of the toe of the shoe in response to the forward pull of the slide bars 75 of the toe band closing mechanism and 90 relieves any unnecessary strain on the bracket or chain 72 which might otherwise be produced by such forward pull. The adjusting screw 86, and connections 84, 82, 74 to the band ends, provides means by 100 which to adjust the tension on the band ends to compensate for the adjustment of bracket 96 made by the screw rod 104.

The chain 72 which is the supporting member affording strength and stability to 105 the toe band is preferably formed, as shown in Figs. 4 and 5, of thin links or plates arranged in vertical series as in the link belt type of construction. In accordance with a valuable feature of this invention there is 110 provided an inwardly and upwardly inclined rigid supporting or backing face for the upper edge portion of the band lining. This is shown as obtained by using links or plates which increase in width or inward 115 extension toward the top of the chain and thereby give to the upper portion of the band the desired inward inclination shown best in Fig. 5.

The band, lining or band as it is commonly 120 designated, as herein shown is of the novel construction disclosed and claimed in United States Letters Patent No. 1,257,670, granted February 26, 1918, upon my application and consists of felt or its equivalent the inner 125 face of which presents a somewhat soft, non-abrasive surface for engagement with the highly finished surface of the material usually employed in the toe caps of shoes, while the felt constituting the outer portion 130

- of the band is suitably treated with shellac as described in said patent to impart to it shape-retaining and wear-resisting qualities. Also the outer face of the band is covered 5 with wear-resisting sheet material 71 which may be leather, canvas, or tough paper applied to it while the shellac is soft, and permanently and intimately attached to the outer face of the band by the adhesive qualities of the shellac.
- Referring again to Fig. 3, it will be noted that the right and left sides of the last illustrated are substantially parallel and both inclined toward the right, this last being one 10 for a left shoe and the inclination being toward that side of the shoe bottom which is outermost when the last is in upright position. To meet this condition and to present the wipers at the plane of the shoe 15 bottom in the same relation to the two sides of the toe so that when they are closed they will lay the upper into position to be fastened at the same distance from the edge and inside the sewing line on both sides of 20 the toe of a McKay shoe is one of the objects of this invention. For this purpose mechanism is here shown for moving the wipers transversely of the machine and of the last while they are being elevated. The plate 13 25 underlying the plate 15 and located between it and the plate 10 has the transverse tongue and groove connection with the plate 10 previously described and seen best in Fig. 1, and the plate 13 is extended at 131, Fig. 3, toward the rear side of the machine where it has a bearing in which is angularly adjustable a slotted block 60 which is in effect a rigid extension of the plate 13, but is adjustable by a hand crank 64 and a screw 30 threaded through an extension 132 of the plate 13. A horizontal rod 62 fixed to the frame of the machine extends through the slot in the block 60. Assuming the block 60 to be adjusted as in Fig. 3, with the slot inclined to the vertical direction of upward movement of the toe lasting mechanism, the action of the stationary rod 62 on the inclined walls of the slotted block will be to move the toe lasting head transversely of the 35 machine as said head rises. This will cause the wipers to move upwardly along the sides of the last in a direction which, by adjustment of block 60, can be made parallel with the sides of the last.
- 50 The toe rest or cushion block 110 by which the forepart of the shoe is upheld against the pressure of the wipers is movable lengthwise of the shoe upon the head 112 of a post 113 which is moved during the jacking operation 55 upwardly through a guide 114 attached to the plate 10. The block is guided on the head 112 by studs 111 extending from the depending flanges of the block into a cam slot 115 cut into the side of the head 112 and formed to permit a limited movement

of the rest block lengthwise of the shoe in a single plane but to guide the block downwardly after it has moved backwardly on the block a short distance. A spring 116 normally holds the block forwardly over the high part of its cam slot. In the unjacking operation the shoe is drawn rearwardly away from the toe lasting mechanism and this construction provides that, after the toe rest has accompanied the shoe for a short distance, the block shall descend along the cam slot 115 and thus relieve frictional engagement of the rest with the shoe and thereby allow the shoe to slide easily off from the toe rest without abrasion.

The guide 114 for the post 113 is connected to the plate 10 by a stem 118 which is held by a spring 120 normally drawn into a socket in the plate so far as an adjustable stop 121 permits. This arrangement provides that after the shoe has been jacked into firm engagement with the toe rest 110 the toe lasting mechanism and the toe rest can be moved together positively toward the rear or heel end of the shoe 90 by the hand wheel 11. Such a movement of the toe wipers is desirable and customary, after they have been closed, in order that they shall force the overwiped upper firmly against the lip of a welt shoe innersole or 95 smoothly back over the toe of a McKay shoe innersole. In the construction shown the toe rest is moved backwardly with the wipers and presses backwardly upon the tip seam. This action on the tip seam is desirable to 100 offset the tendency which the wipers have to bow or bend forwardly the middle portion of the tip seam by reason of their pull upon the upper at the end of the toe. It sometimes happens in the use of the machine, however, that it is necessary to adjust the wipers backwardly from the shoe by the hand wheel 11 in order that they shall properly act upon the shoe. If the toe rest were unyieldingly connected to the plate 10 the 105 toe rest would be moved forwardly by such adjustment of the toe wipers and in doing so would, by its frictional engagement with the upper, tend to bow the tip seam. The yielding connection provided by the stem 118 and spring 120 avoid such action. The stop 121 provides for adjusting the toe rest to different distances from the wipers to locate it at the tip seam for shoes having different lengths of tips.

The inclination of the side faces of the toe to the vertical has been referred to and the automatic bodily movement of the toe lasting devices transversely of the shoe to meet this inclination during their upward wipe 125 has been explained. Such inclination at the sides of the toe is quite generally uniform and in the same direction, that is, toward the outer side of the foot. At the heel portion of the shoe there is also an inclination 130

of the side faces which is very marked at and forwardly from the breast line. There is this difference, however, that at the heel the inclination is inwardly at both sides of the shoe but is much more marked at one side than at the other side. It is found in practice that after the heel lasting mechanism as a whole has been adjusted laterally for the swing of the last, to act uniformly with reference to the median line of the heel part of a crooked last as explained in my prior Patent No. 1,018,477, the heel band is satisfactorily positioned but on some lasts now in use the wipers fail to reach inwardly at the inner side of the heel seat and shank so far as they should do in order to force the upper into its proper relation to the inner-sole. For meeting this condition I provided, in accordance with prior United States Letters Patent No. 1,188,616, granted upon my application Serial No. 706,655, an angular adjustment of the heel wipers with relation to the heel band. I have found, however, that with lasts of the shape above discussed, which have come more recently into use and are characterized by deeply inset shanks, it is difficult satisfactorily to adjust the wipers relatively to the heel band prior to the lasting operation as proposed in said patent, because when the wipers are so adjusted they project inwardly beyond the heel band at the inner side of the shoe so far as to be in the way when the operator applies the last to the heel spindle. To overcome this difficulty I have, by the embodiment of this feature of the present invention illustrated in Fig. 6, provided improved mechanism by which the wipers may stand in the same relation to the heel band at the two sides of the heel of the shoe when the shoe is being inserted in the machine and thereafter the wipers will be angularly adjusted relatively to the heel band toward the outer side of the shoe during the heel seat lasting operation. The illustrated embodiment of this feature of the invention has the important advantage that the angular wiper adjustment is effected automatically or without attention from the operator.

The construction and arrangement of the wiper plates may be substantially as in said Patent No. 1,188,616, or may be as in said Patent No. 1,018,477, except as herein particularly pointed out. As shown in the drawings, each wiper consists of three parts as in said Patent No. 1,188,616 and the wipers are operated by link connections 130 with a cross-bar 132 on the front end of the plunger 134 the rear end of which is secured to the operating lever 135. The wipers have cam slots in which stand studs which are stationary in the wiper carrying plate 136. The peripheral edge of the wiper carrying plate 136 is curved about a center located substantially at the rear end face of the shoe,

and said plate is confined in a correspondingly curved guideway formed by the usual wiper supporting head of the machine and overlying gibs 138.

The wiper carrying plate 136 has a rigid rearwardly projecting arm 140, Figs. 1 and 6, by which it, and therefore the wipers, can be turned. In the rear end of this arm is a stud 141 to the lower end of which is rigidly secured an arm 142 having a longitudinal slot 143. Upon the upper end of stud 141 is rigidly secured an arm 144 carrying a locking bolt 145 to engage one of a series of bolt holes 146 in the arm 140.

A stud 148 stands in the slot 143 in the arm 142 and this stud is carried by a sliding bar 150 movable endwise in a fixed guide and having a transverse slot in its rear end into which projects a stud 152 that rises from the wiper operating lever 135.

The arms 142, 144 rigidly connected at 141 constitute a controller that is adjustable on the arm 140. It may be secured by the locking bolt 145 with the slot 143 in alignment with the path of the bar 150, or it may be adjusted out of alignment toward one side as in Fig. 6 or toward the other side. When out of alignment stud 148, the path of which is predetermined in direction, will force the arms 144, 142, 140 laterally and turn the carrying plate 136 and the wipers toward one side of the machine as an incident to the normal operation of the wipers by their lever 135. The effect of this turning movement of the wiper carrying plate is to advance and close the wipers farther on one side of the heel than on the other side. This is illustrated in Fig. 6 wherein it may be observed that the wiper carrying plate 136 has been turned so as to project its right hand corner forwardly from the front end of the adjacent gib 138 while the left hand corner of the plate is retracted under the gib on that side of the machine. By this movement the wipers have been positioned properly with relation to the bottom of the heel portion of the crooked last which is in the machine and this has been done while the wipers were being advanced and closed by lever 135. More or less bodily turning movement of the wipers as a whole, according to the requirements of the shoe, will be obtained by adjusting arms 142, 144 and fastening them by the bolt 145 in one or another of the holes 146. This adjustment of the wiper operating means compensates for the difference in the shape of the last in the plane of its bottom, with which shape the wipers have to deal, as compared with a plane below the bottom, with which shape the heel band has also to deal. This is indicated in Fig. 7 wherein the adjustment has caused the wiper at the left side of the shoe to be closed and advanced a greater distance than the wiper at the right side has been.

closed and advanced. The end wiper plates 160 are adjustable relatively to the adjacent plates 162 to adapt them to the inward curvature of the shoe bottom at the shank. 5 This adjustment is made as in the machine of said prior Patent No. 1,188,616 by end-wise movable bars 164 having on their front ends studs which stand in slots in the plates. These bars have at their rear ends other 10 studs 165 which stand in oppositely inclined slots formed in the ends of a transverse adjusting bar 166. Movement of the adjusting bar toward one side and then the other of the machine to effect adjustment for rights 15 and lefts is made equal in extent by a slotted link 170 which is pivoted to the bar and embraces a fixed stud 172. The length of the adjusting movement of bar 166 is made variable by a stop screw 174 which limits the 20 effective length of the slot in the link.

The holdown shown in Figs. 1 and 2 is mounted to turn about the axis of a vertical post 179 by which it is moved downwardly to clamp the forepart of the shoe 25 down upon the toe rest. It is advantageous to position the foot plate 180 of the holdown so that it will clamp the innersole close to the end of the toe, but it must be inside the channel lip. In practice operators swing 30 the foot plate forwardly and depress it simultaneously and they often get it too far forward and have to release it and back it away. The holdown mechanism of the illustrated machine is provided with a limiting stop to arrest the forward movement 35 so that the operator is not required to exercise care in respect to the forward position of the foot plate. The stop is indicated at 182, being an adjustable curved plate held 40 upon a stationary cap 183 by a screw 184 passing through a slot in the plate. The swinging head 185 of the holdown has a coöperating stop stud 186.

It has been earlier stated that the toe 45 lasting head is adjustable longitudinally by a screw and hand wheel 11. In practice the screw sometimes turns backwardly under the stresses set up in lasting and as shown herein a brake is arranged to engage the hand wheel 50 and prevent this and comprises supporting members 192, 193, Figs. 1, 2 and 3, a connector 191 extending between said members and affording a radial guide for a brake member 188, the friction lining 187 of which 55 embraces the rim of the hand wheel 11. A spring 190, extending from a stud on the brake member 188 to a stud on the connector 191, holds the brake against the wheel with enough pressure to prevent undesired backward movement of the wipers, but without rendering difficult normal use of the wheel 60 by the operator.

Having explained the nature of this invention and described a preferred construction embodying the same, I claim as new

and desire to secure by Letters Patent of the United States:—

1. A lasting machine having, in combination, last supporting means, end embracing wipers, means for raising the wipers to shape an upper about the side faces of the end portion of the last, and means automatically operative to move the wipers bodily transversely of the shoe while they are being raised. 70

2. A lasting machine having, in combination, last supporting means, end embracing wipers, means for raising the wipers while they are in engagement with the shoe, and means arranged to operate during such upward movement of the wipers for automatically effecting relative bodily lateral movement of the wipers and the end portions of the last. 80

3. A lasting machine having, in combination, last supporting means, end embracing lasting means, means for relatively moving the last and the lasting means substantially perpendicularly to the plane of the shoe bottom to wipe the upper up the sides of the last, and means acting during said relative movement for moving the lasting means transversely of the last during such upward wiping movement. 85

4. A lasting machine having, in combination, last supporting means, end embracing lasting means, means for relatively moving the last and the lasting means perpendicularly to the plane of the shoe bottom while the lasting means is in engagement with the shoe, and means automatically responsive to said relative perpendicular movement for relatively moving the last and the lasting means transversely of the last during the first mentioned movement to maintain wiping engagement of the lasting means with the upper on similarly inclined opposite side faces of the last. 95

5. A lasting machine having, in combination, last supporting means, end embracing wipers, means for raising the wipers to shape an upper about the side faces of the end portion of the last, and means for relatively moving the wipers and the last transversely of the last and proportionally to the 100 upward movement. 110

6. A lasting machine having, in combination, last supporting means, end embracing lasting means, means for relatively moving the last and the lasting means substantially perpendicularly to the plane of the shoe bottom while the wipers are in engagement with the upper, and means dependent upon the first-mentioned movement for causing a relative movement of the last and the last 120 transversely of the last. 125

7. A lasting machine having, in combination, last supporting means, vertically movable toe lasting means constructed and arranged for movement transversely of the 130

- last, and means, responsive to vertical movement of the lasting means, for causing coincident transverse movement of the lasting means.
- 5 8. A lasting machine having, in combination, last supporting means, vertically movable toe lasting means which is also movable transversely of the last, and means arranged for adjustment to cause transverse movement of the lasting means when they are raised.
9. A lasting machine having, in combination, last supporting means, vertically movable toe embracing wipers constructed and arranged for bodily movement transversely of the last to adapt them to follow the inclination of the sides of the toe during their vertical movement, means for effecting vertical movement of the wipers, and means responsive to said vertical movement for causing coincident transverse movement of the wipers.
10. A lasting machine having, in combination, last supporting means, a vertically movable toe lasting mechanism mounted for lateral movement, a co-operating guide and guide-way for controlling the amount of lateral movement, and means for effecting adjustment of the controlling means.
11. A lasting machine having, in combination, last supporting means, a vertically movable stem, lasting means movable transversely of the stem and having a guide arm, a guide co-operating with the arm to effect transverse movement of the lasting means on the stem, and means responsive to vertical movement of the stem for causing the arm to effect transverse movement of the lasting means.
12. A lasting machine having, in combination, last supporting means, end embracing wipers, means for raising the wipers to shape an upper about the side faces of the end portion of the last toward the shoe bottom, and means to cause the lasting means to rise in a predetermined path inclined to the vertical and which can be made substantially parallel with the inclination of the sides of a right last and reversed for a left last.
13. A toe lasting machine having, in combination, means for supporting a last, toe embracing wipers, and operating means to raise the wipers in embracing relation to a last the sides of the toe of which are inclined laterally and to move the wipers automatically into symmetrical lateral relation with the last bottom.
14. A lasting machine having, in combination, a toe support and toe embracing wipers relatively movable to cause the wipers to wipe the upper up the sides of the toe, means for closing the wipers to lay the upper into position to be tacked to the shoe innersole along a line extending around the toe at the inner edge of the wipers, and means to produce automatically a relative bodily lateral movement of the wipers and the toe portion of the last to locate the tacking line at the same distance from each of the two lateral edges of the toe.
15. A machine for wiping an upper up the sides of the toe of a last and inwardly against the lip of a welt shoe innersole having, in combination, a support for the toe of the last, toe embracing wipers, and operating means to impart the relative working movements to the wipers and the last and automatically and coincidentally to impart a relative bodily transverse movement to said wipers and support to cause the wipers to last the upper symmetrically against an innersole lip with relation to which the last is laterally unsymmetrical.
16. A lasting machine having, in combination, last supporting means, a vertically movable end lasting mechanism including end embracing wipers, means to move said mechanism vertically, a rock-shaft having a long operating arm extending into position to be reached by the operator and a short arm and connections normally out of operative engagement with the vertically movable end lasting mechanism, said connections being movable into such engagement with said end lasting mechanism and also serving to depress the wipers by force applied in a single direction to the long arm of the rock-shaft.
17. A lasting machine having, in combination, last supporting means, a vertically movable end lasting mechanism including end embracing wipers, means for raising said mechanism to a position where the wipers can be closed over the shoe bottom, and depressing means including a rock-shaft having a short arm, a bar pivoted thereto and carrying a pawl, ratchet teeth on the vertically movable mechanism to be engaged by the pawl in different vertical positions of said mechanism, a long operating arm on the rock-shaft extending into position to be conveniently reached by the operator of the machine, and means for holding the pawl normally out of engagement with the ratchet teeth.
18. A lasting machine having, in combination, last supporting means, a vertically movable end lasting mechanism including end embracing wipers; and depressing means for said mechanism comprising a rock-shaft having a short arm, a pawl carrier movable on that arm, a co-operating ratchet on said mechanism, operating means for the rock-shaft, a second arm on the rock-shaft, and a cam device movable in the second arm and acting on the pawl carrier to move the latter into engagement with the ratchet during the first portion of the operative stroke of the operating means.
19. A lasting machine having, in combi-

- nation, last supporting means, a vertically movable end lasting mechanism including end embracing wipers; and depressing means for said mechanism comprising a rock-shaft 5 having a short arm, a pawl carrier movable on that arm, a coöperating ratchet on said mechanism, operating means for the rock-shaft, a second arm on the rock-shaft, and a cam device having a stem sliding in said 10 second arm and provided with a cam slot eccentric to the rock-shaft and engaging the pawl carrier to move the latter toward and from the ratchet.
20. A lasting machine having, in combination, last supporting means, a vertically movable end lasting mechanism including end embracing wipers; and depressing means for said mechanism comprising a pawl carrier, a ratchet on said mechanism with which the carrier is normally out of engagement, and operating means for the pawl carrier arranged to effect initial movement of the carrier into engagement with the ratchet and subsequent movement to depress said mechanism by force applied continuously in the same direction.
21. A lasting machine having, in combination, last supporting means, a vertically movable end lasting mechanism including end embracing wipers; and depressing means for said mechanism comprising a pawl carrier, a ratchet on said mechanism with which the carrier is normally out of engagement, and operating means for the pawl carrier including a cam through which initial operating movement will be transmitted laterally to the pawl carrier to effect engagement with the ratchet and which will then yield to allow operative movement to be transmitted downwardly to depress the mechanism.
22. A lasting machine having, in combination, last supporting means, a vertically movable end lasting mechanism including end embracing wipers; and depressing means for said mechanism comprising a rock-shaft, a depressing member held normally out of engagement with said mechanism, and a cam movable by the rock-shaft to effect such engagement and movable thereafter in the rock-shaft while depression of said mechanism is effected by continued movement of the rock-shaft.
23. A lasting machine having, in combination, last supporting devices, a vertically movable end lasting mechanism including end embracing wipers, means for raising and lowering said mechanism; and another means structurally separate from the first means and normally disconnected from said mechanism and comprising a rock-shaft and a connector adapted to pick up said mechanism in any vertical position to which the first means moves it and apply to said mechanism augmented power in the direction to depress the wipers.
24. A lasting machine having, in combination, last supporting devices, a vertically movable end lasting mechanism including end embracing wipers, means for raising and lowering said mechanism; and another means structurally separate from the first means for applying through said mechanism augmented compressive force upon the stock under the wipers.
25. The combination with a work support, a device for operating on the work, and means for imparting a normal full operative movement to said device, of separate means having independent connection to said device for subsequently applying augmented force to said device in the direction of its operative movement.
26. A lasting machine having, in combination, last supporting means, a vertically movable end lasting mechanism including toe embracing wipers; means for raising said mechanism to cause the wipers to work an upper up the side faces of the toe portion of the last embraced by them and to position the wipers in the plane of the toe bottom, means to close the wipers over the margin of the shoe bottom, means additional to and structurally independent of said raising means to depress the wipers to effect substantial compression of the stock located between the wipers and the last, and means for locking the wipers in stock compressing position.
27. A lasting machine having, in combination, last supporting means which is operated to jack and unjack a shoe, a vertically movable end lasting mechanism including end embracing wipers; means for raising said mechanism to cause the wipers to work an upper up the side faces of the toe portion of the last embraced by them and to position the wipers in the plane of the shoe bottom, means to close the wipers over the margin of the shoe bottom, means structurally independent of the raising means to depress the wipers to effect compression of the stock located between the wipers and the last, means for locking the wipers in stock compressing position, and mechanism for operating the shoe supporting means to unlock the depressing means and then unjack the shoe.
28. A lasting machine having, in combination, last supporting means, toe embracing wipers, and operating means for the wipers including means to depress the wipers upon the overlasted margin of the upper on the shoe bottom and means for locking the wipers in a depressed position.
29. A lasting machine having, in combination, last supporting means, a vertically movable toe lasting mechanism including toe embracing wipers and a toe embracing band, means to raise said mechanism and cause the wipers to shape the upper to the side faces.

of the toe, means to close the band to clamp the upper to the side faces of the toe and lock the band under closing pressure, means to close the wipers over the bottom of the 5 toe, means to depress the wipers to shape the upper on the margin of the shoe bottom between the wipers and the last while the band holds the upper on the vertical face of the toe, and means to lock the work under 10 such vertical compression whereby an angular edge is molded at the junction of the side and bottom faces around the toe of the shoe.

30. A lasting machine having, in combination, last supporting means, toe embracing 15 wipers, a toe embracing band, means for operating the wipers, and means for operating the band to clamp the upper to the side faces of the last, said band operating means including slide bars movable longitudinally 20 of the shoe and connected with opposite end portions of the band, abutments coöperating with said slide bars, and means for advancing the bars to tighten the band rearwardly about the toe and for moving the abutments 25 to close the end portions of the band against the sides of the toe.

31. A lasting machine having, in combination, last supporting means, wipers, means 30 for operating the wipers, an end embracing band, and means for operating the band to clamp the upper about the last including a head, wedge bars mounted in said head movable longitudinally of the head and last and connected with opposite ends of the 35 band, and abutments coöperating with the wedges and mounted for relative movement against a yielding resistance.

32. A lasting machine having, in combination, last supporting means, wipers, means 40 for operating the wipers, an end embracing band, and means for operating the band to clamp the upper about the last including a head, wedge bars mounted in said head movable longitudinally of the head and last and connected with opposite ends of the 45 band, abutments coöperating with the wedges, and means for operating the abutments.

33. A lasting machine having, in combination, last supporting means, wipers, means 50 for operating the wipers, an end embracing band, and means for operating the band to clamp the upper about the last including slide bars movable longitudinally of the last 55 and connected with opposite ends of the band, abutments coöperating with the slide bars, means for advancing the slide bars, and means for operating the abutments to force the slide bars inwardly.

34. A lasting machine having, in combination, last supporting means, wipers, means 60 for operating the wipers, an end embracing band, and means for operating the band to clamp the upper about the last including 65 cams pivotally supported adjacent to oppo-

site end portions of the band, and means for simultaneously turning the cams to force the end portions of the band to clamp the shoe upper against the side faces of the last end.

35. A lasting machine having, in combination, an end embracing band, end embracing wipers, means for advancing and closing the wipers, a cam associated with each end 70 of the band, and connections from the wiper closing means to operate the cams.

36. A lasting machine having, in combination, a lasting head, a normally U-shaped end embracing band mounted upon said head, a support by which the middle of the 80 band is held in substantially stationary position relatively to the head during the closing of the band, end embracing wipers, means for advancing and closing the wipers, and connections for applying closing pressure to the ends of the band when the wipers 85 are closed.

37. A lasting machine having, in combination, wipers, an end embracing band, and means for operating the band including 90 slide bars connected with the band ends and movable lengthwise of the shoe and carrying band closing inclines, and relief springs arranged to permit continuation of the movement of said bars and inclines after 95 the inclines have forced the band ends as close against the shoe as they can go.

38. A lasting machine having, in combination, last supporting means, end embracing wipers, means for operating the wipers, 100 an end embracing band, slide bars connected with the band ends, means to move the bars in the direction to force the band ends rearwardly, cams, and means to operate the cams to force the band ends inwardly, said 105 last mentioned means including devices arranged to permit variation in the inward movement at the two sides of the toe relatively to one another.

39. A lasting machine having, in combination, last supporting means, end embracing wipers, means for operating the wipers, an end embracing band, slide bars connected with the band ends, means to move the bars 110 in the direction to force the band ends rearwardly longitudinally of the side faces of the last, abutments arranged to engage the slide bars, and connections from said bar moving means for moving the abutments to force the band ends transversely inward. 115

40. A lasting machine having, in combination, last supporting means, end embracing wipers, means for operating the wipers, an end embracing band, slide bars connected with the band ends, means to move the bars 120 in the direction to force the band ends rearwardly, said bars having rearwardly and inwardly directed inclines on their outer faces near the band ends, cams in contact with which said inclines slide to effect closing 125

of the band when the bars are moved rearwardly, and connections from the bar operating means to move the cams in the direction to increase the closing action of the 5 inclines.

41. A lasting machine having, in combination, end embracing wipers, means for operating the wipers, an end embracing band, slide bars, levers mounted on the slide 10 bars and connected to the band ends, inclines on said slide bars, cams against which the inclines act, and means to move the slide bars endwise and to turn the cams.

42. A lasting machine having, in combination, end embracing wipers, means for operating the wipers, an end embracing band, means for pulling the band ends longitudinally of the shoe, and cams arranged 15 to apply force inwardly to close the band 20 ends and having connection with the pulling means to be turned thereby.

43. A lasting machine having, in combination, end embracing wipers, means for operating the wipers, an end embracing band, means for pulling the band ends longitudinally of the shoe and moving them 25 to apply inward pressure concurrently with the pulling movement, inward pressure supplementing means for the two band ends, 30 and operating means having separately yielding connections with the supplementing means at the two sides of the shoe.

44. A lasting machine having, in combination, end embracing wipers, means for 35 operating the wipers, an end embracing band, and operating means therefor comprising levers each connected at one end to a band end, yielding means connected with the other ends of the levers and having 40 capacity for adjustment to vary the tension of said yielding means, slide bars upon which the levers are secured, and a plunger and operating connections to advance the slide bars.

45. A lasting machine having, in combination, end embracing wipers, means for operating the wipers, an end embracing band, slide bars to which the ends of the band are connected, operating means for 50 advancing the slide bars, inclines on the outer edges of said bars, cam levers having faces on their inner arms located for engagement by said inclines, and yielding connections from the outer arms of said cam 55 levers to the operating means for yieldingly turning the cam levers to apply differential inward pressure to the two ends of the band for adapting the band for right and left lasts.

46. A lasting machine having, in combination, end embracing wipers, means for operating the wipers, an end embracing band, slide bars to which the ends of the band are connected, a lever, a plunger connected 60 to it, a cross-bar on the plunger connected

to the slide bars, cam levers located to engage the inclines on the slide bars, guide rods having connection with the cam levers and the cross bar, and springs on said rods for turning the cam levers as the plunger is 70 advanced.

47. A lasting machine having, in combination, end embracing wipers, an operating lever therefor, an end embracing band, a band operating slide and a lost motion 75 connection permitting initial operation of the wipers by said lever without disturbing the band and then simultaneous operation of the wipers and the band by the wiper operating lever.

48. A lasting machine having, in combination, end embracing wipers, an operating lever therefor, an end embracing band, a band operating slide, and connections permitting initial operation of the wipers by the lever 85 without disturbing the band, then causing closing of the wipers and band together and permitting additional closing of the wipers after the band can close no farther.

49. A lasting machine having in combination, end embracing wipers, an operating lever therefor, an end embracing band, a band operating slide, a lost motion connection permitting initial operation of the wipers by said lever without disturbing the band and then simultaneous operation of the wipers and the band by the wiper operating lever, springs arranged to be compressed to substantial rigidity during the closing of the band and to apply substantially unyielding final band closing pressure.

50. A lasting machine having, in combination, end embracing wipers, an operating lever therefor, an end embracing band, a band operating slide, and a lost motion connection permitting initial operation of the wipers by said lever without disturbing the band and then simultaneous operation of the wipers and the band by the wiper operating lever, said lost motion connection permitting the wipers to be backed off to uncover the tacking line without disturbing the band.

51. A lasting machine having, in combination, end embracing wipers, an operating lever therefor, an end embracing band, a band operating slide and operative connections through which the band is closed by the wiper operating lever including provision for lost motion permitting the wipers to be partially backed off the shoe without opening the band.

52. A lasting machine having, in combination, end embracing wipers, means for operating the wipers, an end embracing band comprising a non-abrasive inner member, a supporting chain therefor secured at its middle, transverse levers to which the ends of the chain are connected, an equalizing 130

bar, spring connections therefrom to the transverse levers, and means for operating the levers to close the band.

53. A lasting machine having, in combination, end embracing wipers, means for operating the wipers, an end embracing band, transverse levers to which the band ends are secured, means for operating the levers to close the band, and means constructed and arranged to provide adjustment for the fulcra of the levers.

54. A lasting machine having, in combination, an end embracing band, slide bars movable edgewise toward and from the band and also lengthwise and having inclines on their outer edges, cam levers to be engaged by said inclines during lengthwise movement of the bars to produce edgewise movement of the bars to close the band ends upon the shoe and connections for positioning the cam levers, and thereby the slide bars edgewise, for right and left shoes during the initial closing movement, said connections thereafter yielding while the slide bars are advanced relatively to the positioned cams to cause the inclines on the bars so positioned to apply approximately equal pressure to the opposite sides of the right or the left shoe end embraced by the band.

55. A lasting machine having, in combination, end embracing wipers, means for operating the wipers, an end embracing band, and operating means therefor comprising slide bars and means to move them, levers fulcrumed on the slide bars and connected at their inner ends to the band ends, an equalizer, and springs connecting the outer ends of the levers to the equalizer.

40 56. A lasting machine having, in combination, end embracing wipers, means for operating the wipers, an end embracing band, and operating means therefor comprising slide bars and means to move them, levers 45 fulcrumed on the slide bars and connected at their inner ends to the band ends, springs attached to the outer ends of the levers, and means connected with the springs and constructed and arranged for adjusting simultaneously the springs for the two levers.

57. A lasting machine having, in combination, end embracing wipers, means for operating the wipers, an end embracing band, and operating means therefor including 55 levers connected at their inner ends to the band ends, an equalizer, and springs connecting the outer ends of the levers to the equalizer, said equalizer comprising two members having a common pivot, said members having short arms adjustably connected together for manipulation to increase or diminish the tension under which the springs are held.

58. A lasting machine having, in combination, end embracing wipers, means for oper-

ating the wipers, an end embracing band, means connected with the closed middle portion of the band by which to adjust the band lengthwise of the shoe relatively to the wipers, and means connected with the 70 ends of the band and constructed and arranged for adjustment to compensate for the adjustment of the middle of the band.

59. A casting machine having, in combination, a lasting head, end embracing wipers, 75 means for operating the wipers, an end embracing band carried by said head, means for holding the band at its middle against displacement longitudinally of the head, means for holding the ends of the band 80 yieldingly tensioned lengthwise of the machine, and means for adjusting the tension with which the band ends are held.

60. A lasting machine having, in combination, a lasting head, end embracing wipers, 85 means for operating the wipers, an end embracing band carried by said head, means for holding the band at its middle against displacement longitudinally of the head, levers connected with the ends of the band, 90 springs arranged to turn the levers in the direction to tension the band ends forwardly, and means connected with the springs acting on both levers for effecting simultaneous and equal adjustment of said 95 springs.

61. A lasting machine having, in combination, a lasting head, end embracing wipers, means for operating the wipers, an end embracing band carried by said head, means for holding the band at its middle against displacement longitudinally of the head, 100 means for holding the ends of the band tensioned lengthwise of the machine, and means for effecting simultaneous adjustment of the 105 tension with which the two ends of the band are held.

62. A lasting machine having, in combination, a lasting head, end embracing wipers, means for operating the wipers, an end embracing band carried by said head, means for holding the band at its middle against displacement longitudinally of the head, supports for the ends of the band, springs 110 connected with the supports at one end, a bar to which the other ends of the springs are attached, and means by which the bar may be secured in different adjusted positions to determine the tension of the springs.

63. A lasting machine having, in combination, end wipers, an end embracing band, means connected with the two ends of the band for operating the band, springs for each band end associated with the said operating means, and means for equalizing the 120 action of said springs at the two sides of the shoe.

64. A lasting machine having, in combination, end wipers, an end embracing band, means connected with the two ends of the 125

- band for operating the band, springs for each band end associated with the said operating means, and an equalizer with which the springs have connection and which is 5 adjustable to vary the tension of the springs.
65. A lasting machine having, in combination, end embracing wipers, means for operating the wipers, an end embracing band, 10 and supporting and operating means for the band including cams acting at opposite ends of the band and which are mounted to turn to clamp the end portions of the band hard against the shoe.
- 15 66. A lasting machine having, in combination, end embracing wipers, means for operating the wipers, an end embracing band, a relatively fixed support, and operating 20 means for the band including cams carried by the support and adapted for operation to force the end portions of the band to clamp the upper materials hard against an end portion of a last.
- 25 67. A lasting machine having, in combination, end embracing wipers and an end embracing band comprising a non-abrasive inner member or lining and a backing therefor having a curvilinear lining-engaging 30 face extending around the upper portion of the lining and inclined inwardly toward the edge of the bottom of the shoe end embraced by said lining.
- 35 68. A lasting machine having, in combination, end lasting wipers and a coöperating shoe end embracing band comprising a non-abrasive inner member or lining for embracing the end of a shoe and a support therefor having an overhanging upper portion embracing the upper portion of the lining to 40 cause said lining, when closed upon the end of a shoe, to engage the end of the shoe along that portion of its side which is adjacent to the shoe bottom.
- 45 69. A lasting machine having, in combination, end embracing wipers, and an end embracing band comprising a non-abrasive inner member or lining and a chain to which the inner member is connected, said chain comprising links or plates arranged in vertical series and decreasing in width from the upper edge downwardly to present an inwardly and upwardly inclined backing surface for the upper portion of the inner member.
- 55 70. A lasting machine having, in combination, end embracing wipers, and an end embracing band comprising a non-abrasive inner member or lining having its end embracing upper edge portion bent inwardly, 60 and a support for said edge portion presenting an inwardly and upwardly inclined lining embracing face to maintain the bent formation of said inner member for engagement around the end of the shoe chiefly at the upper edge of the band.
71. A lasting machine having, in combination, end embracing wipers, means for operating the wipers and an end embracing band of a depth to reach from the edge of the shoe a substantial distance down the side 70 faces of the shoe end and comprising a lining member and a supporting member therefor presenting a curved rigid inwardly and upwardly inclined face for engagement around the lining for a substantial distance. 75
72. A lasting machine having, in combination, end embracing wipers, means for operating the wipers and an end embracing band of a depth to reach from the edge of the shoe a substantial distance down the side 80 faces of the shoe end and comprising a supporting chain which is formed to produce pressure of the band chiefly against the edge of the shoe around its end, and a lining for the chain. 85
73. A lasting machine having, in combination, end embracing wipers, means for operating the wipers and an end embracing band of a depth to reach from the edge of the shoe a substantial distance down the side 90 faces of the shoe end and comprising a non-metallic lining and a metallic backing including a series of articulated members movable to embrace a shoe end, said series presenting upwardly and inwardly inclined faces extending a substantial distance around the lining for pressing the lining against the edge of the shoe. 95
74. A lasting machine having, in combination, end embracing wipers, means for operating the wipers, an end embracing band, 100 means for longitudinally adjusting the band independently of the wipers, and a yielding connection arranged to permit the band to be moved longitudinally of the shoe independently of the operation of the adjusting means. 105
75. A lasting machine having, in combination, end embracing wipers, means for operating the wipers, an end embracing 110 band, operating means for the band including band closing means constructed and arranged to apply a forward pull to the end portions of the band, and means for supporting the middle portion of the band arranged to permit that portion of the band to move toward and against the end face of the last and relatively to the supporting means in response to said forward pull. 115
76. A lasting machine having, in combination, end embracing wipers, means for operating the wipers, an end embracing band, operating means for the band including band closing means constructed and arranged to apply a forward pull to the 120 end portions of the band, means for adjusting the band longitudinally of the machine relatively to the wipers, and a connection between the adjusting means and the middle portion of the band permitting the 125 130

band to move forwardly in response to said pull to engage firmly the end face of the last.

77. A lasting machine having, in combination, end embracing wipers, means for operating the wipers, an end embracing band, means connected with the closed middle portion of the band by which to adjust the band lengthwise on a shoe relatively to the wipers, means for forcing the band ends obliquely inwardly and away from the embraced end of the shoe, the connection between the closed middle portion of the band and the adjusting means permitting play of the band lengthwise of the shoe.

78. A lasting machine having, in combination, toe lasting mechanism movable longitudinally of the machine, and shoe supporting means including a toe rest connected with the toe lasting mechanism to be moved toward the heel end of the machine with said mechanism but to permit movement of said mechanism in the opposite direction independently of the toe rest.

79. A lasting machine having, in combination, toe lasting mechanism movable longitudinally of the machine, and shoe supporting means including a toe rest having a stem which has a horizontally sliding connection with said mechanism, and a spring holding the toe rest to the limit of its movement toward the toe lasting mechanism whereby the rest will be made to partake of movement of the lasting mechanism rearwardly but may cling to the shoe and remain stationary while the toe lasting mechanism is backed away from the shoe, the spring yielding to permit the latter movement and acting to return the rest to normal relation to said mechanism when pressure of the shoe upon it is discontinued.

80. A lasting machine having, in combination, toe lasting mechanism movable longitudinally of the machine, shoe supporting means including a toe rest, a spring holding the toe rest to the limit of its movement toward the toe lasting mechanism whereby the rest will be made to partake of movement of the lasting mechanism rearwardly but may cling to the shoe and remain stationary while the toe lasting mechanism is backed away from the shoe, and means for adjustably determining the proximity to the lasting mechanism to which the spring may return the rest after the pressure of the shoe upon the rest has been relieved.

81. A lasting machine having, in combination, toe lasting mechanism movable longitudinally of the machine and including wipers, a toe rest, and connecting and operating means by which the wipers and also the rest may be moved together rearwardly in engagement with the upper upon the bottom and the top faces of the toe of the last to stretch the upper over the toe of the last

from the edge of the last to the tip seam and the toe lasting mechanism may be reversely moved to back the wipers away from the shoe while the toe rest remains stationary lengthwise of the shoe whereby bowing of the tip seam forwardly is avoided.

82. A lasting machine having, in combination, shoe supporting means, toe lasting mechanism, a hold-down having a post at the rear side of the machine upon which it can be swung in a horizontal plane into operative position over the shoe and by which it may be depressed during such swinging movement into clamping engagement with the shoe, and means to arrest the swinging movement of the hold-down whereby the depression may be completed with the hold-down in the longitudinal relation to the shoe determined by the arresting means.

83. A lasting machine having, in combination, shoe supporting means, toe lasting mechanism adjustable longitudinally of the machine into operative relation to long and short shoes supported on said means, a hold-down movable down upon the shoe and having also a movement forwardly into operative relation to the adjustably positioned toe lasting mechanism, and means for adjustably limiting the forward movement of the hold down.

84. A lasting machine having, in combination, shoe supporting means, end lasting mechanism including toe embracing wipers movable bodily toward and from the shoe supporting means, a screw and hand wheel for effecting such movement, means for operating the wipers to lay the upper over the margin of the bottom of the shoe, means for relatively moving the shoe supporting means and the toe lasting mechanism to effect compression of the overlaid upper upon the shoe bottom, and a brake arranged to hold the hand wheel from movement which would permit the wipers to back away from the shoe during the compressing of the upper on the margin of the shoe bottom.

85. A lasting machine having, in combination, heel embracing wipers, a heel embracing band adapted to close around the heel portion of a last, and operating means constructed and arranged to retract the wipers to a position in which they offer no obstruction to the presentation of a shoe to the band and thereafter to advance the wipers and to close them farther at one side of the machine than at the other side to reach in over a deeply cut-away shank and lay the upper into properly lasted position at both sides of the last bottom.

86. A lasting machine having, in combination, end embracing wipers, and operating mechanism for advancing and closing the wipers including means responsive to wiper closing actuation of the mechanism for effecting a closing movement of the wipers

- of greater length at one side of the shoe than at the other side.
87. A lasting machine having, in combination, end embracing wipers, and wiper operating means constructed and arranged to move the wipers to impart a longer closing movement to the end embracing wipers on one side of the shoe than on the other side.
88. A lasting machine having, in combination, end embracing wipers, operating means for advancing and closing the wipers, and means operated by the advancing and closing of the wipers and constructed and arranged to impart to the wipers closing movement having predetermined differences at the two sides of the shoe end.
89. A lasting machine having, in combination, end embracing wipers, a plate carrying said wipers, means for closing the wipers, and means for operating the wiper carrying plate during the closing movement to cause one wiper to move inwardly farther than the other one.
90. A lasting machine having, in combination, end embracing wipers, a wiper carrying plate, means for closing the wipers, and means actuated through the closing of the wipers for turning the wiper carrying plate during the closing movement about an axis located near the adjacent end of the shoe.
91. A lasting machine having, in combination, end embracing wipers, a wiper carrying plate, means for closing the wipers, and means which can be adjusted to cause the wiper carrying plate to turn and increase the closing movement of one wiper and decrease the closing movement of the other wiper.
92. A lasting machine having, in combination, end embracing wipers, operating means for advancing and closing the wipers, and means automatically operative during wiper advancing and closing movement for causing one wiper to close farther than the other wiper.
93. A lasting machine having, in combination, end embracing wipers, means for operating the wipers, means for adjusting the wipers relatively to their operating means to cause them to reach farther inwardly over the shoe end at one side of the shoe than at the other side, and means for adjustably and equally limiting such movement for right and left shoes.
94. An end lasting mechanism comprising end embracing wipers, operating mechanism for moving the wipers over the work, including means for causing one wiper to close farther over the work than the other wiper, and a controlling means adjustable prior to wiper movement to determine for both wipers the extent of such subsequent closing movement.
95. An end lasting mechanism comprising end embracing wipers, operating mechanism for closing the wipers over the work, and positive operating means effective automatically to close one wiper farther than the other during such closing movement.
96. An end lasting mechanism comprising end embracing wipers, operating mechanism for moving the wipers over the work, and means adjustable prior to wiper movement to cause one wiper to be advanced more than normally and the other less than normally during such subsequent movement.
97. An end lasting mechanism comprising end embracing wipers, operating mechanism for moving the wipers over the work, and means operated by actuation of said mechanism for effecting angular adjustment of the wipers as a unit in the same direction coincidently with movement of the wipers over the work.
98. An end lasting mechanism comprising heel embracing wipers, operating mechanism for moving the wipers over the work, and means adapted to be operated by said mechanism, when actuated to effect angular lateral movement of the wipers as a unit in the same direction about a center located adjacent to the rear end of the heel coincidently with movement of the wipers over the work.
99. An end lasting mechanism comprising a heel embracing band, heel embracing wipers, operating mechanism for advancing the wipers over the work, means for directing the movement of the wipers, and means adapted to be actuated by the operation of said mechanism to adjust the directing means during such wiper advancing movement to cause one wiper to advance differently from the other wiper.
100. A lasting machine, last supporting means, end embracing wipers, an end embracing band, and operating mechanism including means which moves the ends of the band inwardly and is constructed and arranged to permit the sides of the band to be moved farther endwise after they have been moved inwardly as far as they can go.
101. A lasting machine having, in combination, end lasting wipers, an end embracing band and operating mechanism to close the band and tension its sides rearwardly, including tensioning means movable lengthwise of the shoe and closing means, constructed and arranged to permit the tensioning means to continue its lengthwise movement after the band can be closed no farther.
102. A lasting machine having, in combination, end lasting wipers, an end embracing band and operating mechanism to close the band and tension its sides rearwardly, including devices movable to effect closing simultaneously with tensioning, said devices being constructed and arranged to permit continued rearward band movement.

- tensioning movement after band closing movement has been carried as far as the width of the last will permit.
103. A lasting machine having, in combination, end lasting wipers, an end embracing band and operating mechanism to close the band and tension its sides rearwardly including tensioning means movable rearwardly of the shoe and devices co-
10 operating therewith to effect closing of the band through the tensioning means and constructed and arranged to permit continued rearward movement of the tensioning means after the band can be closed no farther.
104. A lasting machine, last supporting means, end embracing wipers, an end embracing band, and operating mechanism therefor comprising band end closing means, springs arranged to transmit closing pressure to the respective band ends, and an equalizer through which such pressure is applied to render the pressure uniform at the two sides of differently shaped right and left lasts.
105. A lasting machine having, in combination, last supporting means, wipers, means for operating the wipers, an end embracing band, and means for operating the band to clamp the upper about the last including slide bars movable longitudinally of the last and connected with opposite ends of the band, abutments coöperating with the slide bars, means for advancing the slide bars longitudinally of the last, and means 35 including an equalizer for operating the abutments to obtain like transverse pressure on the opposite sides of differently shaped right and left lasts.
106. A lasting machine having, in combination, end lasting wipers, an end embracing band and operating mechanism to close the band and tension its sides rearwardly including tensioning means and closing means, and means to equalize the action of
40 the tensioning and closing means at the two sides of right and left shoe ends, said closing means being constructed and arranged to permit continued movement of the tensioning means after the band can be closed no farther.
107. A lasting machine having, in combination, last supporting means, wipers, means for operating the wipers, an end embracing band and means for operating the band to clamp the upper about the last including wedge bars movable longitudinally of the last and connected with opposite ends of the band, abutments coöperating with the wedge bars to move them transversely and mounted for relative movement against a yielding resistance, and means for equalizing the resistance at the two ends of the band.
108. A lasting machine having, in combination, last supporting means, wipers, means for operating the wipers, an end embracing band and means for operating the band to clamp the upper about the last including wedge bars movable longitudinally of the last and connected with opposite ends of the band, abutments coöperating with the wedge bars to move them transversely, and means for operating the abutments, including an equalizer arranged to render the action of the abutments alike on the two sides of right and left crooked lasts.
109. A lasting machine having, in combination, end embracing wipers, an end embracing band, and band closing and tensioning mechanism constructed and arranged to move the ends of the band endwise and inwardly with equal inward pressure at opposite sides of the end portion of differently shaped right and left crooked lasts and to permit the sides of the band to be further tensioned endwise after they have been moved inwardly as far as they can go.
- In testimony whereof I have signed my name to this specification.

MATTHIAS BROCK.
